Robert Endsley,
INVENTOR
BY *Victor J. Evans*

ATTORNEY

UNITED STATES PATENT OFFICE.

ROBERT ENDSLEY, OF CLEVELAND, OHIO.

CORD TAKE-UP.

Application filed April 14, 1925. Serial No. 23,090.

This invention contemplates the provision of an improved cord adjuster, and primarily constructed for use in taking up or adjusting the slack in the conducting cord of an electric appliance to permit of the extension and recession of the cord; and further one which is simple in construction, may be manufactured and sold at a minimum cost and may be easily and readily associated with an ironing board to facilitate the attachment of such or the removal thereof with an ironing board in an expeditious manner.

The invention also aims to provide a novel arrangement and construction of parts to facilitate a quick, convenient and secure attachment of the cord adjuster with an ironing board for retaining the adjuster in an upright and non-obstructing position with respect to the ironing board.

With the above and other objects in view, the invention further includes the following novel features and details of construction to be hereinafter more fully described, illustrated in the accompanying drawing and pointed out in the appended claims.

In the drawings:

Figure 1 is a side elevation of an ironing board with my improved cord adjuster associated therewith.

Figure 2 is a side elevation of the cord adjuster with the holder therefor shown in section.

Figure 3 is a front elevation.

Referring more particularly to the drawings, and in order that a clear understanding of the invention may be had, I have illustrated my improved cord adjuster, denoted by the character 5, as attached to one extreme end of an ironing board A.

To facilitate of a quick and secure connection of the cord adjuster 5 with the ironing board A use is made of a holder which is stamped from a single piece of metal and includes a base 7 and a substantially U-shaped body portion 8. Screws or other suitable fastening means indicated at 9 may be employed for attaching the holder to the ironing board, and such fastening means pass through the ears 10 of the holder. The connecting wall 11 of the holder is stamped out to provide therein a pair of inwardly bulged vertically aligned sockets or straps 12 into

which is inserted the straight shank portion 13 formed at the lower end of the cord adjuster 5, permitting of the latter to be detachably connected with the holder or removed therefrom as the occasion may demand.

The cord adjuster 5 is here shown as formed from a single length of wire or the like material bent at a point adjacent the lower end thereof and at the top end of the shank 13 to provide a pair of coils 14, lending resiliency to the cord adjuster and, as better shown in Figure 1, permits of the extension and recession of the cord when the movement of the electric iron B or the like electrical appliance is desired. The coil 15 is in the nature of a clamp and this clamp receives between the coils or jaws thereof the conducting cord 16 to the iron B.

While it is believed that from the foregoing description the nature and advantages of the invention will be readily apparent, I desire to have it understood that I do not limit myself to what is herein shown and described, and that such changes may be resorted to when desired as fall within the scope of what is claimed.

Having thus described the invention, what I claim as new is:

1. A cord take-up of the character described comprising a metallic holder including a plate having ears extending therefrom and adapted to be connected with a flat surface, a substantially U-shaped body portion rising from said plate, and provided with a pair of spaced vertically aligned sockets formed therein, a cord receiving means associated with said holder and being formed from a single piece of resilient material, coiled adjacent its lower end and thence extended downwardly to terminate in a shank adapted to be inserted in the aligned sockets of the holder for detachable association therewith, and the said material being bent at its upper end to provide a coil forming a clamping means for the cord.

2. As a new article of manufacture, a cord adjuster for use in taking up or adjusting the slack in the conducting cord of an electric appliance, said cord adjuster comprising a single length of resilient material bent to provide on the lower end thereof a shank, coils formed at the point of intersection of

the shank with the adjuster proper, and a second set of coils provided at the extreme upper end of the adjuster and aligning vertically with the former-mentioned coils and a holder including a plate, apertured ears formed on said plate, a substantially U-shaped member rising from said plate, and straps disposed in superimposed relation on said substantially U-shaped member to receive the shank.

10

In testimony whereof he affixes his signature.

ROBERT ENDSLEY.
